PRINT HAMMER

Karsten Solheim, Phoenix, Ariz., and Arlie Jay Duckett, Livermore, Calif., assignors to General Electric Company, a corporation of New York

Filed Sept. 16, 1965, Ser. No. 487,799

3 Claims. (Cl. 101—93)

This invention relates to printing devices and more particularly to printing devices of the class in which successive lines are printed onto a suitable medium in a sequential manner by means of a plurality of hammers which selectively impact the medium with a raised type character.

In the field of electronic data processing, for example, one common means of providing information output is the so-called high speed printer. The high speed printer employs a plurality of movable print characters and a plurality of individually actuated print hammers. One common form of the high speed printer employs a rotatable drum having suitable raised characters arranged in a plurality of rings disposed peripherally around the surface of the drum. Individually actuated hammers are arranged in a row and disposed in opposition to the drum. A suitable printing medium, such as a sheet of paper and an ink impregnated ribbon is disposed between the drum and the hammer. Information is printed onto the paper by causing the hammers to be selectively actuated as the drum is rotated to bring successive characters on the drum into printing position. The actuated hammers impact the paper and ribbon against a printing surface of the raised type character to thus cause an imprinting on the paper. Upon completion of the impact, each hammer rebounds from the paper and is returned to its original or non-actuated position by means of a spring.

Typically, printers of this nature operate at a relatively high rate of speed in order to facilitate the rapid output of information from a processing system. In the state of the present day art, printing speeds upward from 600 lines per minute are common. In the drum printer, in order that each possible character may be printed, it is necessary that the drum rotate one complete revolution for each line of print. Therefore, in a 600-line per minute printer, it is necessary that the drum be rotated 600 times per minute. Inasmuch as a typical drum employs 64 or more characters in each peripheral ring it may be seen that more than 38,000 characters per minute rotate past each of the print hammers so that the time available for actuating a particular hammer to contact a particular character is extremely short and, therefore, extremely short time tolerances must be maintained.

To insure high quality printing it is essential that the printing medium exerts uniform pressure on all areas over the surface of each character which is being printed. This means that a striking surface or face of the hammer which is actuated must be parallel to the printing surface of the character being printed. When magnetic ink is used in printing characters on documents such as bank checks, it is especially important that the character be perfectly formed on the document. Therefore, it is essential that a print hammer be used which will exert essentially uniform pressure over the entire surface of the character being printed. If this were not done, an incompletely printed character can be read by a document reading machine as an entirely different character. For example, an incompletely printed 8 might be read as either a 6 or a 9. For a more thorough understanding of how this might occur, see examples of numerals and the corresponding wave shapes developed by an automatic reading system which are disclosed in a United States Patent 3,000,000 by Kenneth R. Eldredge, filed May 6, 1955, granted Sept.,

2

12, 1961, for an "Automatic Reading System," which is assigned to the same assignee as the present invention.

Print hammers of the prior art are essentially rigid pieces of metal which are mounted opposite the moving print characters. These hammers require elaborate electronic circuitry and ultra high speed actuating mechanisms to obtain the perfect timing required to make a legible character. Even when the timing of the circuit is perfect, poor printing may result as the adjustment of the mechanism is critical, and erratic behavior due to dust or to friction between the hammer and a hammer mount may cause the hammer to produce nonuniform pressure over the printing surface of the print character to thus produce incompletely printed characters.

15 The present invention alleviates the disadvantages of the prior art by providing a print hammer having a flexible portion to enable the face of the hammer to move to assure that the face is parallel to the surface of the character being printed. The face thus exerts essentially uniform pressure over all areas of the surface of the character being printed.

20 It is, therefore, an object of the present invention to provide an improved print hammer to assure uniform printing.

25 Another object is to provide a print hammer which compensates for inaccuracies in timing of the hammer movement.

30 Still another object is to provide a print hammer which exerts essentially uniform pressure over the entire surface of the print character being printed.

35 A further object is to provide a print hammer having a flexibly mounted portion which enables the face of the hammer to move so that the face is parallel to the surface of the print character being printed.

40 The foregoing objects are achieved in the instant invention by providing a print hammer having a resiliently flexible portion between the face of the hammer and a main body of the hammer. If the hammer strikes the printing medium when the printing surface of a character is not parallel to the face of the hammer, the flexible portion bends so that the face of the hammer becomes parallel to the printing surface of the character. The face of the hammer thus exerts essentially uniform pressure over the entire surface of the character being printed.

45 As the flexible portion bends, the face of the hammer moves relative to the main body so that the face is moved across the sheet over the surface of the character in a wiping motion which aids in causing the ink to print the entire character onto the sheet being printed. If the hammer strikes the printing medium when the printing surface of a character is parallel to the face of the hammer, printing is accomplished without the bending of the flexible portion.

50 Other objects and advantages of the present invention will become apparent from the following description taken in connection with the accompanying drawings wherein:

55 FIG. 1 is a view, in side elevation, of a first embodiment of the instant invention as it might be utilized in a high speed printer;

60 FIGS. 2 and 3 are enlarged views, partially broken away, of the invention shown in FIG. 1, and illustrating the operation of the present invention; and

65 FIG. 4 is a view, in side elevation, of a second embodiment of the instant invention as it might be utilized in a high speed printer.

70 With specific reference now to FIG. 1, there is shown a first embodiment of the present invention as it might find use in a drum printer, with the present invention comprising a projectile type print hammer 11. Hammer 11 is positioned opposite a drum 12 having a plurality of

print characters 14, 14a, 14b, etc., located around the periphery of the drum 12 which is rotated at a constant speed by a motor, not shown. A printing medium 16, including a sheet of paper 18 and an ink impregnated ribbon 20, is disposed between the drum 12 and hammer 11. Ribbon 20 is supported by a pair of ribbon guides 21. Hammer 11 is biased toward the right by a spring 22 so that it does not cause printing medium 16 to engage the print characters until the desired print character 14 is moved into proper printing position. When the desired character 14 moves into printing position, a means 24 for impinging the hammer 11 onto medium 16 is activated. Means 24 includes a propelling means or lever 26; a spring 28 which biases lever 26 toward the hammer 11; and a catch 30 which prevents the lever 26 from activating the hammer 11 until the lever is released.

When it is desired to print a character the catch 30 is moved downward by means, not shown, thereby releasing lever 26 and allowing the lever to strike a body member 32 of hammer 11. Hammer 11 is then impelled toward the drum causing a face or striking surface 34 of the hammer to impinge against medium 16. The hammer is directed, in its flight toward the drum, by a pair of hammer guides 36 so that the hammer impacts medium 16 against a printing surface 38 of print character 14 causing this character to be printed upon sheet 18. The hammer rebounds from medium 16 and is secured against hammer mount 36. Lever 26 is returned to the non-actuated position illustrated in FIG. 1 by a suitable means not shown.

The ink impression of character 14 which is formed upon sheet 18 is dependent upon the position of the face 34 of the print hammer in relation to the printing surface 38 of print character 14. Therefore, the following discussion will pertain to the relative positions of hammer 11 and character 14.

The hammer, as best seen in FIGS. 2 and 3, includes a main body member 32, a head 40 and a resiliently flexible neck portion 42. The neck portion has a cross sectional area which is substantially smaller than the cross sectional area of either the head or the body member so that this neck portion can more easily bend or flex.

FIG. 2 illustrates an enlarged view of hammer 11 and character 14 which are shown in FIG. 1. In FIG. 2 the print drum has rotated into an ideal position so that the printing surface 38 of print character 14 is parallel to the face 34 of print hammer 11. When hammer 11 is impelled toward the left, face 34 strikes medium 16 and causes this medium to strike the entire surface 38 of character 14 resulting in the complete printing of the character on the paper.

FIG. 3 illustrates the advantages of the present invention. The hammer head 40 is connected to the body member 32 by the resiliently flexible neck portion 42. This neck portion allows the head 40 to be moved in relation to the body member 32 and results in the complete printing of the character upon the paper even when the print drum is not in an ideal position. If the hammer (FIG. 3) is impelled toward character 14 before the drum has rotated into the ideal position, the lower portion of face 34 of the print hammer causes medium 16 to strike the lower portion of the printing surface 38 so that an incompletely printed character would result if a prior art hammer without the flexible neck portion were used. However, in the present invention when face 34 impacts medium 16 against surface 38, the resiliently flexible neck portion bends as shown by the dashed lines of FIG. 3. The head 40 of hammer 11 is moved into the dashed line position shown in FIG. 3 so that face 34 is parallel to the printing surface 38 of character 14. As a result, face 34 exerts essentially uniform pressure over the entire surface 32 of print character 14. An additional benefit provided by the present invention concerns a wiping action which is obtained when the face 34 of hammer 11

moves from the solid line position to the dashed line position shown in FIG. 3. The lower portion of face 34 moves downward over surface 38, thereby producing a wiping action which squeezes ink from the ribbon and aids in providing a completely printed character.

To insure high quality printing, the timing of the hammer stroke should be adjusted so that a typical stroke of the hammer causes the lower portion of printing surface 38 to first make contact with the printing medium between surface 38 and face 34 to thus insure a slight wiping action at all times. This typical stroke should occur when the character 14 is between the position shown in FIG. 2 and the position shown in FIG. 3. If a subsequent hammer stroke were slightly delayed, the hammer face would strike the printing medium when the character is near the position shown in FIG. 2. If another hammer stroke were a little early, the hammer face would then strike the printing medium when the character is near the position shown in FIG. 3. In either of these extreme cases the character would be completely printed as discussed above.

There has been shown and described a print hammer which alleviates the problems of circuit timing and erratic behavior of the print hammer. Because the neck portion of the hammer is flexible the adjustment of the timing of the hammer stroke is less critical than in printers using prior art hammers. High quality printing can be obtained as this neck portion flexes to also compensate for erratic behavior due to friction between the hammer and the hammer mount. The flexing of the neck portion so that hammer face 34 is parallel to printing surface 38, and the wiping action described above combine to produce a more completely printed character than is obtained with prior art print hammers.

FIG. 4 illustrates a second embodiment of the invention shown in FIGS. 1-3 wherein like parts have similar reference characters. FIG. 4 differs from FIG. 1 in that it employs a pivotedly mounted print hammer 11' instead of a projectile type print hammer. Impacting means 43 strikes hammer 11' causing it to rotate counterclockwise about a pivot 44. Hammer head 40' is moved toward the left causing face 34' to strike sheet 18 forcing it against ribbon 20 and print character 14 in a manner similar to that described in connection with FIG. 1. When the printing surface 38 of print character 14 is parallel to face 34', printing is accomplished as was described in connection with FIG. 2. When face 34' is not parallel to printing surface 38, the resiliently flexible neck portion 42' of the hammer bends as was described in connection with FIG. 3.

Thus, resiliently flexible neck portion 42' can be used with either a projectile type print hammer shown in FIG. 1 or with the pivotedly mounted print hammer shown in FIG. 4.

While the principles of the invention have now been made clear in an illustrative embodiment, there will be immediately obvious to those skilled in the art many modifications of structure, arrangement, proportions, the elements, materials, and components, used in the practice of the invention, and otherwise, which are particularly adapted for specific environments and operating requirements without departing from those principles. The appended claims are therefore intended to cover and embrace any such modifications, within the limits only of the true spirit and scope of the invention.

What is claimed is:

1. A print hammer for use in a printer having a printing medium located between the print hammer and a rotatable print drum, said printer having means for impinging said hammer onto said medium to impact the medium against a printing surface of a print character formed on the drum, said hammer comprising: a main body member; a hammer head including a surface adapted to strike said medium and to impact said medium against the printing surface of said character; and a re-

silently flexible portion, said portion serving to connect said head to one end of said member, said portion being asymmetrically connected to said head to provide a portion which flexes when the surface of said head impacts the medium against the surface of said character to effect parallel alignment of the two surfaces, said portion causing said head to return to its original position relative to said member when the surface of said head no longer makes contact with the medium.

2. A print hammer for use in a printer having a printing medium located between the print hammer and a rotatable print drum, said printer having means for impinging said hammer onto said medium to impact the medium against a printing surface of a print character formed on the drum, said hammer comprising: a projectile type body member; a hammer head including a surface adapted to strike said medium and to impact said medium against the printing surface of said print character; and a resiliently flexible portion having a cross sectional area substantially smaller than the area of said head, said portion serving to connect said head and one end of said member, said portion being asymmetrically connected to said head to provide a portion which flexes when the surface of said head impacts the medium against the surface of said character to effect parallel alignment of the two surfaces, said portion causing said head to return to its original position relative to said member when the surface of said head no longer makes contact with the medium.

3. A print hammer for use in a printer having a printing medium located between the print hammer and a rotatable print drum, said printer having a means for impinging said hammer onto said medium to impact the medium against a printing surface of a print character formed on the drum, said hammer comprising: a pivotally mounted body member; a hammer head including a surface adapted to strike said medium and to impact said medium against the printing surface of said character; and a resiliently flexible portion, said portion serving to connect said head to one end of said member, said portion being asymmetrically connected to said head to provide a portion which flexes when the surface of said head impacts the medium against the surface of said character to effect parallel alignment of the two surfaces, said portion causing said head to return to its original position relative to said member when the surface of said head no longer makes contact with the medium.
